UNITED STATES PATENT OFFICE.

DIMITRI SENSAUD DE LAVAUD, OF PARIS, FRANCE, ASSIGNOR, BY MESNE ASSIGNMENTS, TO CENTRIFUGAL PIPE CORPORATION, A CORPORATION OF DELAWARE.

ROTARY MOLD.

Application filed August 27, 1910, Serial No. 406,444. Renewed May 6, 1922. Serial No. 559,073.

To all whom it may concern:

Be it known that I, DIMITRI SENSAUD DE LAVAUD, a citizen of the United States of Brazil, and resident of Paris, France, have 5 invented certain new and useful Improvements in Rotary Molds, described in the following specification and illustrated in the accompanying drawings, that form part of the same.

10 The principal objects of the invention are to overcome the difficulties met with in water jacketing rotating molds resulting from the expansion and contraction of the mold under the intermittent excessive heat to which the 15 mold is subjected and to devise a structure which will be simple and inexpensive to make.

The principal feature of the invention consists in the arrangement of expandible 20 ring sealing members between the mold and the end walls of the water jacket encircling same and providing longitudinal cylindrical contact surfaces to slidably engage said sealing rings.

25 In the drawings Figure 1 is an elevational view in part section of a mold constructed in accordance with this invention.

Figure 2 is a cross section through the mold and water jacket showing the rotatable 30 supports for the mold.

Figure 3 is an enlarged longitudinal sectional view of the mold wall showing the piston ring seal for the water jacket.

35 Figure 4 is a view similar to Figure 1 showing a modification of the water jacket structure.

In the form of device herein shown the 40 rotatable mold 1 is mounted on rollers 2 supported within the outer cylindrical casing 3 and arranged so as to balance the weight of the mold longitudinally and support it axially within the outer casing.

The outer casing 3 is spaced from the 45 mold a distance sufficient to form a water jacket of such dimensions that the water contained therein will absorb the heat of the molten metal poured into the mold and radiating therethrough during the solidifying of the metal.

50 At one end of the casing 3 the inner wall is formed with the annular grooves 4 and 5 and in the outer of these grooves is inserted a ring 6 which engages a flange 7 on the bell end of the mold 1, a packing ring 8 being

inserted therebetween and forming a water 55 tight joint.

A ring 9 is seated in the groove 5 and the inner periphery 10 is spaced from the mold and presents a cylindrical surface parallel with the mold. The periphery of the mold 60 1 is provided with an annular groove 11 opposed to the surface 10 of the ring 9 and in this groove is placed a spring piston ring 12 which forms a flexible sealed joint between the mold and the ring 9. The flexible 65 seal thus provided allows for the annular and longitudinal expansion and contraction of the mold without binding and always maintains a water tight joint.

A pair of rings 13 and 14 similar to the 70 rings 9 are arranged at the opposite end of the casing and the inner cylindrical surfaces thereof engage in water sealing contact with the piston rings 15 and 16 housed in the grooves 17 and 18 in the flange 19 of 75 the mold 1.

It will be understood from this description that a water jacket is formed around the mold 1 which will offer no material resistance to the rotation of the mold even 80 when at its maximum heat and it will also be readily seen that the roller supports 2 for the mold will allow it to move freely in expansion and contraction.

Water is fed to the jacket through a pipe 85 20 entering the casing 3 adjacent to the ring 9 and is carried away by the overflow pipe 21 at the opposite end. The water need not be under any more pressure than is necessary to cause circulation through the water 90 jacket.

The mold is rotated by a "Pelton wheel" 22 arranged on the mold 1 between the rings 9 and 6 and the bell end of the mold is cooled by the water projected into the wheel 95 and circling the compartment between said rings.

The outer casing 3 is preferably formed in sections so that if it is desired to change the size of the mold, the upper section may 100 be removed and the mold and rings may then be lifted out and another substituted therefor.

In the structure shown in Figure 4 the bell end 23 of the mold has secured to its 105 flanged end 24 a cylindrical member 25 which is spaced from the periphery of the mold and carries the "Pelton wheel" 22.

Piston rings 26 and 27 are housed in peripheral grooves at each end of the member 25 and these are engaged by ring members 28 and 29 secured in the outer casing 3.

5 This construction allows the water jacket to extend the full length of the mold. Cross reference is hereby made under the provisions of Rule 43, to my copending application, Serial No. 559,072.

10 What I claim as my invention is:—

1. In a rotary mold, the combination with the cylindrical mold rotatably supported and a casing encircling the mold and spaced therefrom to form a water jacket, of flexible 15 piston rings encircling the mold and engaging the mold and casing to form a water seal.

2. In a rotary mold, a cylindrical casing, a rotary mold axially supported in said 20 casing, ring members secured in said casing and extending toward the periphery of the mold, and expansible piston rings carried by the mold and slidably and rotatably engaging said ring members.

25 3. In a rotary mold, a cylindrical casing, roller supports arranged in the lower half of said casing, a cylindrical mold resting on said roller supports and having annular 30 grooves in its periphery, expansible piston rings arranged in said grooves, and ring

members forming end walls of a water jacket secured in said casing and having cylindrical inner faces engaging in sliding and rotative contact with said piston rings.

4. In a rotary mold, a cylindrical casing, 35 a rotary mold axially supported in said casing and free to expand circumferentially and longitudinally, said mold having cylindrical flanges at the ends spaced from the periphery of the mold to allow water contact for the entire length of the mold, annular grooves in said cylindrical flanges, piston rings in said grooves, and ring members secured to the casing at each end and provided with cylindrical surfaces to engage 40 said piston rings.

5. In a rotary mold, a cylindrical casing, a rotary mold axially supported in said casing and free to expand circumferentially and longitudinally, a "Pelton wheel" 50 secured to the mold at one end, ring members secured to the casing each side of said "Pelton wheel," ring members arranged at the other end of the casing, and piston rings sealing the space between said mold and 55 said ring members.

Signed at New York, in the county of New York and State of New York, this 30 day of July, A. D. 1920.

DIMITRI SENSAUD DE LAVAUD.
